1576 L Jr. Henry Berger of New York N.Y. DES. 2430

Letters Patent No. 2430, Dated Sept. 25, 1866

Design for a Centrepiece

The schedule refers to in these letters Patent and marking a part of the same.

To all whom it may concern:

Be it known that I, Henry Berger of No. 95, 14th Avenue in the City, County and State of New York have invented a new Design for Centrepiece, and I do hereby declare that the following is a full, clear, and exact description thereof, enabling those skilled in the art to fully understand and use the same, reference being had to the accompanying drawing.

The drawing represents a plan of this invention. The distinguishing features of this Design are a diamond border with concave sides ornamented by arabesques on its corners and on the middle of its sides. The middle portion of the diamond shaped centre piece is ornamented by a cento resembling a forget-me-not, from which emanates a series of leaves and which is situated in the middle of a branch of leaves. From said leaves emanate a series of curved branches which fill up the space between the inner border which is composed of a series of hemispherical or shell-like projections and which is separated from the outer border by a plain concave member.

A, represents the outer border of my centrepiece which is diamond shaped with concave sides. Said border is ornamented on its corners with arabesques B, and on the middle of its concave sides with arabesques C.

D, is the inner border which is separated from the outer border by a concave member E, and said inner border surrounds the diamond shaped space F, which is ornamented by a cento G, resembling a forget-me-not, from which radiates a number of leaves H, and which is situated in the middle of a branch I, of leaves. From this branch emanate the curved branches J.
